INVENTOR

John A. Klein,
Ad. Snow & Co.

UNITED STATES PATENT OFFICE.

JOHN A. KLEIN, OF JOANNA STATION, PENNSYLVANIA.

LOCK-HINGE.

SPECIFICATION forming part of Letters Patent No. 244,621, dated July 19, 1881.

Application filed June 10, 1881. (No model.)

To all whom it may concern:

Be it known that I, JOHN A. KLEIN, of Joanna Station, in the county of Berks and State of Pennsylvania, have invented certain new and useful Improvements in Hinges; and I do hereby declare that the following is a full, clear, and exact description of the invention, which will enable others skilled in the art to which it appertains to make and use the same, reference being had to the accompanying drawings, which form a part of this specification.

Figure 1 is a perspective view. Fig. 2 is a top plan. Fig. 3 is a horizontal sectional view. Fig. 4 is a view of the leaves separated, and Fig. 5 is a detail view of the latch.

Corresponding parts in the several figures are denoted by like letters of reference.

This invention relates to hinges for window shutters and blinds, which said hinges are so constructed as to retain the shutters or blinds in an open position when so adjusted, a suitable spring-latch being employed for this purpose, as will be hereinafter fully described, and particularly pointed out in the claim.

In the drawings hereto annexed, A represents the main leaf of the hinge, the inner edge or shoulder of which is provided with the upward projecting pintle or spindle B, upon which the leaf C is hinged in the usual manner, as shown.

The leaf A is provided with a chamber or socket, D, to receive the latch E. The latter is provided with a vertical longitudinal slot, F, by which it slides upon the pintle B, between

which and the front end of the latch a spring, 35 G, is interposed to force the said latch in a forward direction.

The leaf C of the hinge is provided with a flange, H, extending horizontally, as shown, and provided with a notch, I, which, when the hinge is one-fourth open, will enable the leaf C to be lifted off the main leaf A, thus enabling the shutter or blind to be removed. When in any other position the leaves A and C are inseparably connected.

From the foregoing description, taken in connection with the drawings hereto annexed, the operation and advantages of my invention will be readily understood. The construction is simple and inexpensive, and my improved hinge is more easily adjusted and operated than shutter-fastening devices of a more complicated construction.

Having thus described my invention, I claim and desire to secure by Letters Patent of the United States—

The combination of the leaf A, having socket D, notched and longitudinally-slotted latch E, spring G, and the leaf C, having notched flange H, substantially as herein described, for the purpose shown and specified.

In testimony that I claim the foregoing as my own I have hereto affixed my signature in presence of two witnesses.

JOHN A. KLEIN.
